UNITED STATES PATENT OFFICE.

ADOLPH S. STIEFEL, OF NEW YORK, N. Y.

FOLDING PAPER BOX.

SPECIFICATION forming part of Letters Patent No. 536,162, dated March 19, 1895.

Application filed January 18, 1895. Serial No. 535,358. (No model.)

To all whom it may concern:

Be it known that I, ADOLPH S. STIEFEL, a citizen of the United States, residing at New York, in the county of New York and State of New York, have invented certain new and useful Improvements in Folding Paper Boxes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The present invention relates to the class of folding paper boxes specially designed for confectionery and small commodities, and the object in view is to provide a box which shall present in outline and general appearance the fac simile of a church, house, building or similar structure, when set up.

To this end the invention consists of a folding box of a special configuration which has bottom flaps and look therefor of any approved pattern, to form the bottom of the box, and an upper side extension, so constructed as to form a closing flap and present the appearance of a roof, all as hereinafter fully described and set forth in the claims.

In the accompanying drawings: Figure 1 is a view of the box blank proper, forming the sides and bottom of the box, and cover supports, and Fig. 2 is a view of a secondary blank to be attached to the main blank by gumming or otherwise to form the box cover. Fig. 3 shows the bottom of the box with the flaps closed. Figs. 4 and 5 are end and side views respectively of the closed box, and Fig. 6 illustrates the closing action of the cover.

The blank A is cut of a length sufficient to form the four sides of a box and with the end extension a, which is to be attached to the opposite end of the blank, by gumming or otherwise. Crease lines b, b, b, b, mark the corners of the box, and the intervening sections terminate at the top in the angular extensions, a', a², a³, a⁴, and at the bottom the several sections have the proper flap extensions C, D, E and F for forming the bottom of the box. The flaps C and E are shown provided with tongues and slots respectively for forming a lock, but any flap lock may be employed

that is suitable for the purpose. Crease lines for the bottom flaps are indicated at c, d, e and f.

Extending out from one of the sides of each of the angular top extensions, a' and a³, there are triangular flaps, a⁵ and a⁶, with crease lines between a', a⁵, and a³, a⁶, respectively, and the cuts shown at a⁷ and a⁸ are for the insertion of the ends of a tape handle, G.

The secondary blank H, forming the box cover, is rectangular in shape, with the end extensions, h' and h², the former being a hinge flap for attaching it to the main blank at the base of the angular piece a⁴, as indicated in dotted lines in Fig. 1, and to hold one end of the tape handle, and the latter forming a tongue for holding this cover flap closed. A crease line at h³ marks the bend of the flap over the apex of the angular box ends. The width of this cover piece is greater than the width of the box, so that it extends over the ends of the box and thus insures a close fit between the cover flap and the box ends, as well as accentuating the effect of a roof. It will be observed that the angular extensions, a², a⁴, come inside of the tape handle, when the box is in use, and serve to hold the handle distended, as well as forming ears for the attachment of the tape ends, while they also carry out the general design and effect sought for. The extension a² also forms a guiding surface for directing the tongue h² of the cover flap down into its slot, when closing down the cover. This slot for the tongue of the cover is formed by the bottom edges of the flaps a⁵, a⁶, and the inner face of the piece a² at the base of the triangle. When the box is set up the flaps a⁵ a⁶ lie in a plane perpendicular to the plane of the ends, a' and a³, and parallel with the inclined surface of the front of the cover flap when it is closed down, the points of the flaps a⁵ a⁶ just meeting. There is thus formed a slot between their bottom edges and the inner face of a², which receives the tongue h², and the flaps a⁵ a⁶ also serve the further purpose of stiffening the gable ends, a', a³, and preventing them from being pushed either in or out when the box is filled, the flaps a⁵ a⁶, lying just beneath the cover flap and on top of the contents of the box.

The general effect of the box may be enhanced by ornamentation printed or embossed

on the box as indicated in Figs. 4, 5 and 6, but the same is not a necessary adjunct of the invention.

What I claim as new is—

- 5 1. A four sided folding box having bottom flaps and lock therefor, angular extensions at the top of the several sections forming both the sides and ends of the box, a handle attached to the angular extensions at the top 10 of the side sections, and a cover flap attached within one of the box sides, said cover flap being wider than the length of the box and adapted to fold down over the tops of the box ends, with a tongue for fastening down the 15 cover, substantially as and for the purpose set forth.
2. A folding box having angular extensions

at the top of two of the opposed sections forming the sides of the box, with inwardly turned opposed flaps carried by the same respectively on one edge, and a cover flap extending up from one of the intermediate sides of the box and adapted to fold down over the tops of the box ends, said cover having a tongue which fits in between the edges of the inwardly turned flaps and the side of the box, substantially as and for the purpose set forth. 20 25

In testimony whereof I affix my signature in presence of two witnesses.

ADOLPH S. STIEFEL.
